ALARM DEVICE

Walter M. S. Kilgour, Lexington, Mass.

Application October 9, 1929. Serial No. 398,494

10 Claims. (Cl. 200—81)

My invention relates to alarm devices for fluid distributing systems, as for example, wet or dry pipe automatic sprinkler systems for fire protection.

5 The invention, which has among its objects the provision of an alarm device responsive to flow of fluid in the system, with avoidance of leakage of fluid, and avoidance of complex mechanical parts, the latter to insure certainty of operation and to 10 enable the device to be constructed and maintained at minimum cost, will be best understood from the following description when read in the light of the accompanying drawings of one embodiment of the invention, the scope of which 15 latter will be more particularly pointed out in the appended claims.

In the drawings:—

Fig. 1 is a longitudinal vertical section, with parts in elevation, of an alarm valve constructed 20 according to the invention;

Fig. 2 is a longitudinal vertical section of the valve according to Fig. 1, with the parts in different positions;

Fig. 3 is a section on the line 3—3 of Fig. 1 with 25 parts omitted;

Fig. 4 is a fragmentary section of the valve, on an enlarged scale, on the line 4—4 of Fig. 3; and

Fig. 5 is a diagram representing the switch in different operative positions.

30 Referring to the drawings, I have shown a casing 1 formed to provide a chamber 3, the casing having openings 5 and 7 respectively forming a fluid inlet and a fluid outlet for the chamber 3.

As illustrated, fluid communication between 35 the inlet connection 5 and outlet connection 7 may be established and interrupted by a valve, which valve herein constitutes a flow responsive device, and comprises a head indicated in its entirety at 9, mounted on an arm 11, the latter pivoted for swinging movement on trunnions 13 and 15 (Fig. 3).

As shown, the valve head 9 comprises a flange portion 17 and a plug portion 19, both of which portions cooperate with a bushing 21 screw threadedly secured in the discharge end of the inlet opening 5. When the valve arm 11 is in its lowest position (as shown by Fig. 1) the lower face 23 (Fig. 2) of the flange portion 9 of the valve head is adapted to seat against the end face 25 of the bushing. Adjacent the end face 25 the bushing is formed with the internal annular surface 27, the annular surface of the plug portion 19 of the valve head being formed to fit this surface with a minimum clearance, with the result 55 that the valve may move to its dotted line position in Fig. 1 before the valve opens, with the result that fluid communication between the inlet and outlet connections of the chamber 3 is not established by water hammer or slight fluctuations of 60 pressure in the system.

The valve head above described conveniently may be made by molding it of suitable substances such as hard rubber compound commonly employed for valves. As shown, the body of the valve head is molded about a stud 28 having the 65 flange head 29 and screw threaded shank 31, the shank from about midway its length to its end opposite the head 29 being of reduced diameter to provide a shoulder 33. Herein, the free end of the valve arm 11 has a perforation 35 formed to provide a shoulder 37, through which perforation the shank of the stud extends, the shoulder 33 of the shank abutting the shoulder 37, the parts being so proportioned as to provide a space 39 between the adjacent faces of the arm and valve 75 head. A nut 41 on the shank 31 holds these parts in assembled position.

As shown (Fig. 4) the valve head 9 is provided with a small diameter bore or perforation 43, passage of fluid through which is controlled by a 80 check valve, which herein is in the form of a plate 45 on the upper side of the valve head. The plate 45 has a body portion which extends through the space 39 between the valve head and valve arm, this body portion being perforated to have 85 a loose fit on the shank 31 so that the latter serves as a guide for the plate. The perforation 43 permits a slight flow of fluid through the valve when the pressure of the fluid in the piping connected to the inlet connection 5 rises, as would 90 be the case, for example, if the system were supplied with water from city mains, while the check valve 45 prevents a back flow of this fluid. In cases where the valve is installed in systems in which the pressure does not vary, the perforation 95 43, if desired, may of course be omitted.

As shown, for holding the valve head 9 in proper relation to the valve seat afforded by the bushing 21, and for holding the plate 45 in proper relation with the passage 43 through the valve head, a pin 47 is provided which, as clearly shown by Fig. 4, extends through aligned perforations in the arm 11, plate 45, and valve 9. For securing durability the pin 47 is shown as secured in a perforation in the flanged head 29 of the stud about which 100 the valve head is molded.

As shown, the shank 31 beyond the nut 41 is provided with a buffer 49 of cushion material, such as rubber, for cooperation with the stop 51 carried by the upper wall of the casing.

Herein the valve arm 11 adjacent its trunnion supports is provided with a hollow boss 53 providing a chamber 55. This chamber, at the lower portion thereof, has a diaphragm or shelf 57 for supporting a tilt-operated switch, the latter actuated into open and closed circuit positions by 115 swinging movement of the valve arm for controlling an alarm.

As shown, the switch comprises a block 59 of insulating material, such as so-called bakelite, 120

molded about the head 61 of a metal stud, the latter having a screw threaded shank 63 which extends through an insulating bushing 65 received in a central perforation of the shelf 57, a nut 67 screw threaded on said shank securely holding the block 59 in assembled relation with the valve arm 11.

Herein, the block 59 is provided with a chamber 69 which has a conical bottom wall 71, the apex of the latter being formed in the upper surface of the stud head 61. The upper end of the chamber 69 is closed by a plate 73 of insulating material, such as bakelite, which plate on its under side, as viewed in Fig. 4, has a plug 75 extending downwardly into the chamber into proximity with the conical wall 71, so as to provide between said wall and the adjacent end of the plug a more or less restricted annular passage 77. As shown, a contact pin 79 is screw threaded 20 into the plug 75 and projects below the lower face of said plug into proximity with the apex of the conical wall of the chamber 69. Herein, for securing the plate 73 in assembled relation with the block 59, flanged sleeves 81 and 83 are fitted 25 over the lower and upper ends of the block and are soldered or welded together at their overlapping portions 85. The contact pin 79 is provided with a head 87 between which and the upper surface of the plate 79 is a metal plate or washer 89, to which is secured, by soldering or welding, the end of a lead 91, a second lead 93 being secured to a metal plate or washer 95 between the nut 67 and the insulating bushing 65.

With the switch as above constructed, tilting 35 of the arm 11 from the position shown by Fig. 1 to that shown by Figs. 2 and 4 will cause a globule of mercury 97, contained in the chamber 69, to place the contacts afforded by the pin 79 and the upper portion of the stud head 61 into electrical communication. Conveniently, the parts 40 may be so designed that the line A (Figs. 4 and 5) on the conical wall 71 will be in horizontal position when the plug 19 of the valve head 9 is in its dotted line position shown in Fig. 1.

The operation of the switch is diagrammatically illustrated in Fig. 5, in which "Position A" indicates the position assumed by the circuit breaker when the valve is closed as shown by Fig. 1. Under these conditions the globule of 50 mercury 97 is out of contact with the stud head 61 and contact pin 79. "Position B" shows the position of parts when the arm swings upward to move the valve head just past the line A on its dotted line position in Fig. 1, in which position 55 the conical surface 71 is just past the horizontal. This movement causes the globule of mercury 97 to move as a body from its position shown in "Position A" to its position shown in "Position B", in which latter position the contact pin 79 and stud head 61 are placed in electrical communication. "Position C" represents the conditions when the valve arm 11 is in the position shown in Figs. 2 and 4, under which conditions the stud 60 head and contact pin are maintained in electrical communication by the globule of mercury.

The restricted passage 77 between the upper and lower portions of the chamber 69 acts to cause the mercury to move from its position in "Position A" to its position in "Position B" suddenly as a globule, so that the circuit will be closed suddenly, and likewise be opened suddenly when the valve arm is moved in the opposite direction. The restricted passage also prevents opening of the switch under the influence of vibration of the parts. The rapid closing of the

switch is also effected by reason of the plug 19 of the valve first leaving the seat 27 at the lowermost portion of the latter, which causes the valve to open suddenly when fluid is discharged in desired volume from the part of the system connected to the outlet 7 of the casing 1.

As illustrated, the upper portion of the arm 11 is provided with bores 99 and 101, respectively receiving and having bearings on the trunnions 13 and 15. The bore 101, as diagrammatically indicated in Fig. 5, communicates with the chamber 55 at opposite sides of the shelf or partition 57. The leads 91 and 95 pass through the bore 101, and the trunnion support 15, to the exterior of the casing 1.

As shown, the trunnion support 15 is screw threaded into the casing wall, and has an axial perforation 103 which, for a short portion of its length adjacent its inner end, has a "pinch fit" 90 with the rubber sheathing 105 for a cable containing the leads 91 and 95. Inwardly of this latter portion, the perforation 103 is, for a portion of its length, of enlarged diameter, and filled with shellac insulating compound or other suitable insulating and waterproof material. The 100 extreme outer portion of the bore 103 is of further enlarged diameter, as shown at 107, to provide a shoulder 109 against which rests a plate 111, the latter having a perforation through which the cable extends. Extending into the 105 enlarged diameter portion 107 of the bore 103 is a packing bushing 113, of rubber or the like, which bushing, at its inner end, abuts the plate 111, and, at said end, has the conical exterior 110 surface 115, the latter cooperating with a gland nut 117 screw threaded into the outer end of the bore for pressing the portion of the packing adjacent the conical surface tightly into engagement with the cable. The packing 113, in conjunction with the sealing compound in the bore 115 115 120 125 130 135 140 145 150 155 160 165 170 175 180 185 190 195 200 205 210 215 220 225 230 235 240 245 250 255 260 265 As shown, the boss 53 on the arm 11 is provided with a rearward extension 131 which, in conjunction with said boss and the parts contained therein, serves as a counter-weight for the 5 valve head. As illustrated, the extension 131 is formed with a cam track 133 cooperating with a roller 135 for actuating a lever 137 fulcrumed at 138 on the casing 1. On the upper end of this lever is a valve 139, herein provided for serving 10 as a pilot valve to cause actuation of a main valve 141, which latter permits escape of fluid from the chamber 3 when the valve 9 is open, the escaping fluid actuating a so-called water alarm, which alarm commonly is in the form of a turbine-actuated gong. Conveniently, the spring 142 constantly urges the lever 137 to rotate on its fulcrum in such direction as will hold the roller 135 against the cam track 133.

As illustrated, the valve 141 comprises a central stem carrying, at opposite ends thereof, piston heads 143 which are reciprocably mounted in a bore 145. This bore, at the lower end thereof, is placed in communication with the seat for the valve 139 by a passage 147, so that when the 25 valve 139 is in its open position shown by Fig. 2, pressure fluid will be admitted from the chamber 3 to the lower end of the bore 145 and will raise the valve 141 against the force of a compression spring 147, which spring constantly urges the 30 valve 141 to its lowest position shown by Fig. 1. The lower end of the bore 145 is of reduced diameter, as shown at 151, to provide a shoulder 153, the latter affording a stop for limiting the downward movement of the valve 141. This 35 lower reduced diameter portion of the bore is placed in communication with the atmosphere by a bleed pipe 155 communicating with the bore by a passage of smaller effective cross-sectional area than the effective cross-sectional area of 40 the passage 147, with the result that there is available a unit pressure for lifting the valve 141 less than the unit pressure of the fluid in the chamber 3. When the valve 139 is closed to interrupt communication of the passage 147 with 45 the chamber 3, the fluid will be discharged from the lower end of the bore 145 through the bleed pipe 155 to permit the valve 141 to return to its lowermost position.

As shown, the intermediate portion of the bore 50 145, that is to say, the portion thereof between the piston heads 143, in all positions of the valve 141 is placed in communication with the chamber 3 by a passage 157. A second passage 159 positioned above the passage 157, as viewed in 55 Figs. 1 and 2, is placed in communication with the passage 157 when the valve 141 is in its raised position, as shown by Fig. 2, while such communication is interrupted when the valve is in its lower position, as shown by Fig. 1, with the 60 result that the water alarm will be actuated when the parts are in the position shown by Fig. 2, and will not be actuated when the parts are in the position shown by Fig. 1.

Preferably the vertical width of the port 65 through which the passage 159 communicates with the bore 145 is not greater than the vertical width of the upper piston head 143 of the valve 141, so that said upper head 143 will have entered the portion of the bore 145 above this port when 70 communication is established between the passages 157 and 159, with the result that upward movement of the valve will be cushioned by trapped air in the upper portion of said bore. The degree of cushioning is controlled by a small 75 diameter bore 161 extending through the plug

163 closing the upper end of the bore 145, this bore also preventing the formation of a vacuum in the upper end of said bore when the valve 141 is permitted to move downwardly, the bore 161 also assuring that no water will be trapped in the upper end of the bore 145 to prevent full movement of the valve 141.

It will be understood that the valve herein described may be used in various situations in connection with distributing systems for various fluids. As shown, it may be employed in place of the so-called main automatic sprinkler valve heretofore commonly used at the main water entrance for the sprinkler supply system of a building. It also may be used as a so-called supervisory alarm valve for branch supplies to separate sections of the sprinkler system, in which case the water alarm features may be omitted. The valve is particularly adapted for use in connection with branches of a sprinkler system supplying sprinkler heads in different rooms, in which case the valve, which may be made small, may actuate annunciators at a central point, remote from the rooms, for indicating that the sprinkler heads in particular rooms are discharging water.

It will be understood that although but one specific embodiment of the invention has been illustrated and described, wide deviations may be made from this embodiment without departing from the spirit of the invention.

I claim:

1. An alarm valve structure for fluid distributing systems having, in combination, a casing having a chamber, a fluid inlet and a fluid outlet for said chamber, a swinging flow-actuated valve in said chamber having a plug portion, a seat for said valve cooperating with the plug portion thereof for establishing fluid communication between said inlet and outlet when said valve is moved in one direction past a position between the ends of its travel and for interrupting such communication when moved in the opposite direction past said position, a tilt-operated electric switch in said chamber operatively carried by said valve for movement therewith, said switch being arranged for changing alternately from one circuit controlling condition to another as said valve is moved to said position alternately in opposite directions.

2. An alarm valve structure for fluid distributing systems having, in combination, a casing having a chamber, a fluid inlet and a fluid outlet for said chamber, a valve in said chamber mounted for swinging movement, said valve having a plug portion, a seat for said valve cooperating with said plug portion thereof for establishing fluid communication between said inlet and outlet when said valve is moved in one direction past a position between the ends of its travel and for interrupting such communication when moved in the opposite direction past said position, a tilt-operated electric switch in said chamber operatively carried by said valve for movement therewith, said switch being arranged for changing alternately from one circuit controlling condition to another as said valve is moved to said position alternately in opposite directions.

3. An alarm valve structure for fluid distributing systems having, in combination, a casing having a chamber, a fluid inlet and a fluid outlet for said chamber, a swinging flow-actuated valve in said chamber having a plug portion, a seat for said valve cooperating with the plug portion thereof for establishing fluid communication between

- said inlet and outlet when said valve is moved in one direction past a position between the ends of its travel and for interrupting such communication when moved in the opposite direction past 5 said position, means forming a chamber operatively carried by said valve for movement therewith, a body of mercury in said chamber, and contact means cooperating with said body for causing the latter alternately to change said 10 switch from one circuit controlling condition to another when said valve is moved to said position.
4. An alarm valve structure for fluid distributing systems having, in combination, a casing having a chamber, a fluid inlet and a fluid outlet 15 for said chamber, a swinging valve in said chamber, said valve having a plug portion, a seat for said valve cooperating with said plug portion thereof for establishing fluid communication between said inlet and outlet when said valve is moved in one direction past a position between the ends of its travel and for interrupting such 20 communication when moved in the opposite direction past said position, means forming a chamber operatively connected to said valve for movement therewith, the last mentioned chamber having an internal surface which is in a horizontal 25 position when said valve is in said position, a body of mercury in said chamber supported by said surface for movement thereon as a globule, and contact means cooperating with said body of 30 mercury for causing said body alternately to establish and interrupt an electric circuit when said valve is swung alternately in opposite directions to cause said surface to be inclined alternately in opposite directions from its horizontal position.
5. An alarm valve structure for fluid distributing systems having, in combination, a casing having a chamber, a fluid inlet and fluid outlet for 35 said chamber, a cooperating valve and valve seat in said chamber for establishing and interrupting fluid communication between said inlet and outlet, said valve and seat being relatively formed for permitting said valve to move in opening direction a predetermined amount before establishing 40 substantial communication between said inlet and outlet, an electric switch in said chamber, said switch having different circuit positions, and operative connections between said valve and switch for causing the latter to be maintained 45 in one of said circuit positions during movement of said valve from its closed position to approximately its position in which said substantial communication is established and thereupon to change to another circuit position.
- 55 6. An alarm valve structure for fluid distributing systems having, in combination, a casing having a chamber, a fluid inlet and fluid outlet for said chamber, a cooperating valve and valve seat in said chamber for establishing and interrupting fluid communication between said inlet and outlet, said valve and seat being relatively formed for permitting said valve to move in opening 60 direction a predetermined amount before establishing substantial communication between said inlet and outlet, a tilt actuated electric switch in said chamber, operative connections between said valve and switch for tilting the latter in response to movement of the former, said connections being effective to maintain said switch in one circuit position during movement of said valve from its closed position to approximately 65 its position in which it establishes said substan-
- tial communication and thereupon to change to another circuit position.
7. An alarm valve structure for fluid distributing systems having, in combination, a casing having a chamber, a fluid inlet and fluid outlet for 70 said chamber, a cooperating swinging valve and valve seat in said chamber for establishing and interrupting fluid communication between said inlet and outlet, said valve and seat being relatively formed for permitting said valve to move in opening direction a predetermined amount before establishing substantial communication between said inlet and outlet, and a tilt actuated electric switch in said chamber operatively carried by said valve for movement therewith, said switch having different circuit positions, and being maintained in one of said circuit positions during movement of said valve from its closed position to approximately its position in which said substantial communication is established and thereupon changing to another circuit position. 80
8. An alarm valve structure for fluid distributing systems having, in combination, a casing having a chamber, a fluid inlet and fluid outlet for 85 said chamber, a cooperating swinging valve and valve seat in said chamber for establishing and interrupting fluid communication between said inlet and outlet, said valve and seat being relatively formed for permitting said valve to move in opening direction a predetermined amount before establishing substantial communication between said inlet and outlet, means forming a chamber carried by said valve, a body of mercury in said last mentioned chamber, said body movable in said chamber by tilting of said valve, and contact means cooperating with said body of 90 mercury for establishing and interrupting an electric circuit as a valve moves in opposite directions respectively past approximately its position in which said substantial communication is established and thereupon changing to another circuit position. 95
9. An alarm valve structure for fluid distributing systems having, in combination, a casing having a chamber, a fluid inlet and fluid outlet for 100 said chamber, fluid flow responsive means in said chamber comprising a swinging member, a trunnion for supporting said swinging member, said trunnion carried interiorly of said chamber by a wall of said casing, an electric switch in said chamber actuated by said flow responsive means, 105 said trunnion having an axial perforation leading to the exterior of said casing, and a lead for said switch extending through said perforation of said trunnion to the exterior of said casing. 110
10. An alarm valve structure for fluid distributing systems having, in combination, a casing having a chamber, a fluid inlet and fluid outlet for 115 said chamber, a substantially cylindrical interior valve seat, an arm mounted for swinging movement, a flow-actuated valve carried by said arm comprising a plug cooperating with said valve seat, said plug and seat being so shaped and disposed that said plug first leaves said seat at one side thereof at an intermediate position of its travel whereby the valve is moved in opening 120 direction abruptly from said position, and a tilt operated electric switch carried by said arm for movement therewith, said switch being operative to change circuit connections when moved to a position which corresponds to said intermediate 125 position of travel of said plug. 130
